UNITED STATES PATENT OFFICE.

WILLIAM PASSMORE MEEKER, OF MAPLEWOOD, NEW JERSEY.

GLASS TILE.

972,461.

Specification of Letters Patent. Patented Oct. 11, 1910.

Application filed June 3, 1908. Serial No. 436,370.

To all whom it may concern:

Be it known that I, WILLIAM PASSMORE MEEKER, a citizen of the United States and of the State of New Jersey, residing at 5 Maplewood, Essex county, New Jersey, have invented certain new and useful Improvements in Glass Tiles, of which the following is a specification.

My invention relates to glass facing tiles 10 having finished faces upon one side and suitable securing means upon the other side, and consists in the particulars hereinafter set forth.

In the drawings Figures 1 and 2 are re- 15 spectively front and back views of the tile.

Similar letters of reference designate similar parts in both the figures.

My improved tiles are provided upon their backs with outwardly inclined holding 20 lugs as shown near their upper edges in the drawings, and with hook-like lugs, $k' k'$ near their opposite edges. Each of these hook-like lugs $k' k'$ is inclined alternately in opposite directions, its base being inclined 25 to one side of a line perpendicular to the back of the tile, and, preferably, parallel to the lug near the opposite edge of the tile,

while its top portion is disposed at an angle to said base portion and inclined to the opposite side of said perpendicular line, so that 30 these hook-lugs $k' k'$ will be positively locked in place in the cement backing to which the tile may be applied, both by their own form and by the divergent disposition of the lugs upon the opposite edge of the 35 tile, while their thin and flat characteristics give the advantage of allowing adjustment of the cement past them in the process of setting.

Having thus described my invention, what 40 I claim and desire to secure by Letters Patent of the United States is:—

A glass facing tile provided upon its back with an integral lug having a base portion inclined to one side of a line perpendicular 45 to the back of the tile, and a top portion disposed at an angle to said base portion and inclined to the opposite side of said perpendicular line.

WILLIAM PASSMORE MEEKER.
